[57] ABSTRACT

A reglet joining clip for particular use with a panel glazing system wherein a plurality of reglets are employed to define a glass retaining frame extending around a wall opening. Each clip includes a base dimensioned to closely embrace a portion of the bottom walls of adjacent channel areas and upwardly extending leg members extending substantially coextensively with the support area edges to resiliently engage the side walls of the adjacent channel areas. The clips, each relatively short in length, are formed in a continuous strand with the interconnecting portions being either bendable or frangible. One clip is used for joining adjacent longitudinally disposed reglets and two, interconnected, clips are used for joining adjacent reglets which form a frame corner.

A STRAND OF INTEGRAL CLIP MEMBERS

This is a continuation of Application Ser. No. 136,848 filed Apr. 23, 1971, and now abandoned.

DISCLOSURE

The application pertains to the art of panel sealing systems and more particularly to a new reglet joining clip for use with such panel sealing systems.

The present invention is particularly applicable to window sealing systems for use with concrete walls wherein reglets are generally cast into the walls around a window opening wherein the reglets define the means for mounting a window panel and will be described with particular reference thereto; however, it will be appreciated that the invention has broader applications such as wherever it may be desirous of joining adjacent reglets in a predetermined desired relationship relative to each other for mounting any type of construction components.

Reglets are elongated channel shaped members of extruded plastic which form the means for holding a window pane in the window opening of a concrete wall. Usually they are placed in their ultimate position and the concrete is then cast around the outer sides of the channel. To insure that the reglet is firmly attached to the wall, the outside of the channel usually is provided with laterally extending flanges.

Heretofore, when reglets were imbedded in concrete walls or the like, there have been no means provided to interconnect adjacent reglets. This made it difficult to maintain the adjacent reglets in the desired aligned relationship in order to form a desired window panel mounting gasket receiving channel. This problem was particularly acute when the concrete walls were poured around the reglets in that the force of pouring often caused the reglets to become misaligned relative to the other reglets comprising the retaining frame. As a result, it was necessary to utilize a single or continuous reglet for each side of the retaining frame to be formed. This practice, of course, developed a substantial number of "scrap" reglet segments in that once a reglet length was cut to size, that portion remaining could not be used unless it was long enough to form a complete retaining frame side elsewhere. Obviously, a substantial amount of scrap was inherent with this type of use.

Further, when preparing a multi-sided frame, for example, a rectangular frame for a corresponding rectangular opening, it was necessary to miter or bevel the ends of the adjacent corner forming reglets in order that they could be closely fitted together in a desired spaced relationship. This mitering step necessitated rather precise angled cuts to be made which, required substantial time and skill to perform. As these corner reglets were not rigidly affixed to each other, the pouring and vibrating of the concrete around them often caused misalignment as described above. These mitered corners were also necessary to prevent the concrete or other construction material from entering the ends of and fouling the reglet channel areas.

The present invention contemplates a clip for holding the reglets in aligned relationship which overcomes all of the above referred problems and others, which clip is simple to manufacture, easy to use, adaptable to any reglet mounting requirement and is provided in strip form with other identical clips in order that the clips may be removed therefrom as needed.

In accordance with the present invention, there is provided a reglet joining clip comprised of a channel having a base dimensioned to generally transversely span at least a portion of the bottom walls of a reglet and upstanding walls for resiliently engaging the side walls of a reglet. The length of the clip is such as to overlap the ends of adjacent reglets and hold them in position.

In accordance with a more limited aspect of the present invention, there is provided a reglet joining clip integral with at least another identical clip at the bases only so that the individual clips may be bent to an angle relative to each other or broken apart.

In accordance with another more limited aspect of the present invention, there is provided a reglet mounting clip wherein the joining portions of the base are of a lesser thickness than the base area itself in order to provide means for separating the clip from its integral connection with other identical clips.

In accordance with still another aspect of the present invention, there is provided a strand of reglet joining clips comprised of a plurality of identical reglet joining clips, means for interconnecting each of the plurality in an end to end relationship with at least another of the clips and means for separating each of the plurality of clips from each other.

The principal object of the present invention is the provision of a reglet joining clip which may be used to rigidly affix adjacent reglets to each other in a predetermined desired aligned relationship.

Another object of the present invention is the provision of a reglet joining clip which eliminates the necessity for mitering or beveling the ends of those reglets forming frame corners.

Another object of the present invention is the provision of a reglet joining clip which permits the use of short or odd lengths of reglets in forming a side of a panel retaining frame.

Still another object of the present invention is the provision of a new reglet joining clip which prevents concrete or other building materials comprising a building wall from entering the reglet channel areas at the corner joints of a panel retaining frame.

Yet another object of the present invention is the provision of a new reglet mounting clip which is simple and economical to manufacture.

Yet another object of the present invention is the provision of a new strand of identical interconnected reglet mounting clips in which any number of individual clips may be easily removed therefrom for application with a panel mounting system.

The invention may take physical form in certain parts and arrangement of parts, a preferred embodiment of which will be described in detail in the specification and illustrated in the accompanying drawings which form a part hereof and wherein:

FIG. 1 is a plan view, with portions of the wall broken away, of a window mounted in a concrete wall illustrating a preferred embodiment of the invention;

FIG. 2 shows two mounting clips in accordance with the subject invention as they are used in rigidly connecting two reglet members forming a corner for the frame shown in FIG. 1;

FIG. 3 is a cross sectional view taken along line 3-3 in FIG. 2;

FIG. 4 is a perspective view of the two reglet joining clips used in FIG. 2; and,

FIG. 5 shows a portion of a strand of the reglet joining clips of the subject invention with one of the reglet clips being broken away therefrom.

Referring now to the drawings, wherein the showings are for the purposes of illustrating a preferred embodiment of the invention only and not for purposes of limiting same, the FIGURES show a panel 10 mounted in an opening 12 in a concrete wall 14. Panel 10 could comprise any type of construction panel, however, in the preferred embodiment, this panel is a glass window pane. similarly, wall 14 could be formed from other construction materials. Disposed about opening 12 in concrete wall 14 are a plurality of reglets 16, portions of which are more precisely shown in FIGS. 2 and 3. This type of panel mounting system is known in the art as may be seen more completely in my copending and commonly assigned continuation-in-part application Ser. No. 89,954 and the commonly assigned U.S. Pat. No. 3,524,290. These reglets are received in gasket receiving channels 18, integrally formed in concrete wall 14 when the wall is poured around the prepositioned reglets, which face inwardly towards opening 12. An elastomeric gasket member 20 has a tongue (not shown) which is received in the reglets and includes means for retaining panel 10 in a desired position relative to opening 12. Again, this type of arrangement is known in the art and is shown in the above mentioned commonly assigned application and patent.

More specifically, in this type of sealing system, reglets 16 each include a channel area 28 comprised of a pair spaced apart side walls 30, 32 joined together by a bottom wall 34. the bottom wall has a generally flat outer surface area 35. Disposed on the inside of side walls 30, 32, and extending longitudinally therewith, are a plurality of inwardly extending protrusions 36, 38 respectively. Similarly disposed on the outside surfaces of the side walls are a plurality of outwardly extending protrusions 40, 42. It is to be noted that protrusions 36, 38 matingly engage a tongue member (not shown) on gasket 20 as is known in order to maintain the gasket in a desired panel sealing relationship with panel 10. Similarly, protrusions 42, 44 engage the sides of reglet receiving channel 18 in concrete wall 14. As reglets 16 are generally placed in position prior to pouring the concrete wall, the reglets are permanently retained in receiving channels 18 by these outwardly extending protrusions; however, other methods of locating the reglets relative to the wall may be used without affecting the operation or scope of the reglet joining clip of the subject application. Disposed coextensive with bottom wall 34 are outwardly extending bottom wall extensions or wings 44, 46 which also serve to retain the reglets in their respective receiving channels 18, but which also are used with the subject clip as will be hereinafter described.

Each reglet 16 also includes shoulder areas 48, 50 including downwardly extending longitudinal retaining protrusions 52. Some reglets may also include break-off tabs 54, 56 which increase the shoulder width of the reglets but which may be easily removed if a thin shoulder area is preferred due to construction requirements. Other shoulder configurations have also been heretofore utilized, it only being necessary for purposes of the subject invention that reglets include a channel area as hereinabove described.

The joining clip of the subject invention is best shown in detail in FIGS. 3 and 4 and specific reference will be

made thereto. The joining clip itself is generally designated 60 and includes a base or bottom 62 and upwardly extending legs 64, 66. In the preferred embodiment, these clips are stamped and formed from a thin, relatively rigid metal. It will be understood, however, that other materials, such as plastic, could be utilized. In the preferred embodiment, base 62 is dimensioned to be received in a closely embracing relationship with outer surface area 35 of bottom wall 34. In the preferred embodiment, legs 64, 66 each comprise a longitudinal outwardly extending curvilinear surface 68 adjoining the side edges of base 62 and a longitudinal inwardly extending a curvilinear surface 70 adjoining surface 68. As can best be seen in FIGS. 4 and 5, legs 64, 66, i.e., surfaces 68, 70, extend substantially over the length of base 62. However, it will be noted that legs 64, 66 each include tapered ends 72, 74 which converge upwardly from the base intermediate adjacent ones of the opposite base ends of each individual clip 60. The taper on each end may be of any angle, however, in the preferred embodiment, an angle of no greater than 45° measured relative to base 62 is preferred as will hereinafter become apparent relative to the use of the clip.

Each clip includes identical joining areas 80, 82 (FIG. 5) at the ends thereof which areas are bendable through an angle of at least 90° without breaking but upon repeated bendings are frangible. Essentially, areas 80, 82 are merely extensions of base 62; however, in the preferred embodiment, it should be noted that the ends of areas 80, 82 are notched to a thickness less than the thickness of the base.

The joining clip of the subject invention is most advantageously formed in a strand generally designated 90 with other identical clips and are interconnected by joining areas 80, 82 in an end to end relationship. As the ends of the joining clips are notched to a thickness less than the thickness of the support area, a notch 94 is formed between each joining clip 60 and the adjacent joining clips at the associated joining areas 80, 82. Each notch 94 extends transversely across the strand.

Two uses of the subject reglet joining clip are shown in FIG. 1, namely, in joining together lengths of reglets in order to form a single elongated reglet and in forming a corner joint for the panel retaining frame. These uses are generally designated A, B, respectively in the FIGURES. In joining two adjacent lengths of reglets only one clip 60 is utilized. In order to remove this one clip from the strand shown in FIG. 5, it is merely necessary, due to notches 94, to repeatedly bend the clip arcuately back and forth about notch 94 as shown by directions *a* and *b* therein. The result of this bending is to establish metal working stress areas at the notch so that a fracture will occur across the notch following only a few bending cycles. As best seen in FIG. 4, this fracture establishes slightly uneven or jagged edges 96 on joining areas 80, 82; however, these uneven edges do not affect the operation or use of the clip. The fact that the clips may be broken away from the strand by this arcuate bending movement is important for job site use in that it eliminates the need for any metal cutting tools for the separation process. Alternatively, of course, a pair of tin snips could be used to make the separation.

Once this single clip has been removed from strand 90, it is ready for installation to secure the two adjacent reglets 16 together by merely snapping or sliding the

clip in position on one end of a reglet as best shown in FIG. 3, such that approximately one half the length of base 62 closely embraces outer surface area 35 of that reglet. The clip may be "snapped on" the reglet by placing the clip in the desired position with curvilinear surfaces 70 of legs 64, 66 in longitudinal engagement with bottom wall extensions or wings 44, 46 and then exerting a pressure against base 62 so that surfaces 70 are biased outwardly from each other to permit the clip to pass into a tight fitting relationship with the reglet whereby base 62 closely embraces outer surface area 35. In this position, extensions or wings 44, 46 are received in outwardly extending curvilinear surfaces 68 of the legs. As the clip is formed from a resilient material, surfaces 70 spring back toward each other to lock the clip into place once the extensions or wings are received in the outwardly extending curvilinear surfaces. This same above described procedure is then repeated relative to the other reglet length in order to form the completed reglet.

In order to complete corner joint B, shown in FIGS. 1 and 2, two of the clips of the subject invention are required. It is therefore necessary to remove two interconnected clips from strand 90 as hereinabove described. Once removed and as best shown in FIGS. 2 and 4, these two clips are then bent at notch 94 so that they are generally normal to each other. In the preferred embodiment, the taper of ends 72, 74 is 45° when measured from their respective support areas. Therefore, when the two clips are bent the normal position with each other, these tapers come together at an abutting joint 98 to completely enclose the joint area and aids in preventing the concrete or other construction material from entering into the reglet channel areas. With particular reference to FIG. 2, the horizontally disposed reglet is then placed in position in its associated clip as has been hereinabove described. It should be noted that there is a small gap c between the end of this reglet and base 62 of the vertically extending clip. This distance should not exceed the total height of legs 64, 66, again, in order to prevent the concrete or other construction material from entering the reglet channel area during pouring. The vertically disposed reglet may then be inserted into the vertically extending clip with the reglet leading edge closely engaging the shoulders of the horizontally extending reglet member.

The length of each clip as measured longitudinally along base 62 need not be substantial. It is only necessary that it be sufficient to clampingly engage the adjoining reglets and provide some rigidity for the joint. It has been found that for reglets having a channel width of $\frac{3}{4}$ inch and a channel height of 1 inch, a clip length of 2 inches is entirely satisfactory.

Although the subject clip has only been shown for use in connecting two longitudinally abutting reglets and for use in forming a generally square corner joint, it will be appreciated by those skilled in the art that other combinations of the subject clip may be used to perform other clipping functions as required by the very nature of the reglet use requirements. For example, it would be possible to seal a panel which does not have square corners, in which case, the combination of two clips described in this specification and drawings would be bent to whatever degree dictated by the panel shape. Further, various numbers of the clips could be

used in addition to the number described with reference to joints A and B in FIG. 1.

The invention has been described with reference to the preferred embodiment. Obviously, modifications and alterations will occur to others upon the reading and understanding of this specification. It is my intention to include all such modifications and alterations insofar as they come within the scope of the appended claims or the equivalence thereof.

10. Having thus described my invention, I now claim:
  1. A strand of integral clip members, each clip member including a substantially flat base portion having opposite longitudinal edges and leg members integral with said base portion and extending upwardly from said edges, each said leg member being reversely curved so that one of said leg members has a substantially S-shaped cross-sectional configuration and the other of said leg members has a substantially backward S-shaped cross-sectional configuration, each leg member having an outwardly extending curved portion adjacent said base portion and merging into an inwardly curved portion, said leg members having terminal end portions extending outwardly from said inwardly curved portions and terminating at terminal ends facing outwardly of said base portion, said base portion having opposite base ends and said leg members having substantially V-shaped notches therein extending down to said base portion intermediate adjacent base ends.
  2. The clip member strand of claim 1 wherein said leg members have opposite leg ends sloping upwardly toward one another from said base ends at angles less than ninety degrees to form said V-shaped notches.
  3. The clip member strand of claim 2 wherein said leg ends slope upwardly toward one another from said base ends at angles of substantially forty-five degrees.
  4. The clip member strand of claim 1 wherein said base portion includes a pair of base portions on opposite sides of said notches, said base portions being joined by a transverse bendable joining area, and said notches being shaped so that bending said base portion along said transverse bendable joining area to cause said pair of base portions to extend substantially perpendicularly to each other causes the sides of said notches to substantially contact one another and to substantially bisect the angle formed between said pair of perpendicular extending base portions.
  5. The clip member strand of claim 1 wherein said base portion has opposite base ends integrally connected with base ends of adjacent substantially identical clip members at transverse bendable and frangible joining areas, said legs having opposite leg ends sloping toward one another from said base portions at angles less than ninety degrees to define said V-shaped notches at said joining areas.
  6. The clip member strand of claim 5 wherein said notches have diverging sides defined by said leg ends and said sides slope at substantially 45° to said base portions.
  7. A strand of integral clip members integrally connected at transverse bendable and frangible joining areas, each of said clip members including a base portion having opposite base edges and opposite base ends, leg members integral with said base portion and extending upward from said opposite base edges, said base ends of adjacent clip members being integrally connected at said joining areas, said leg members on each of said clip members having opposite leg ends sloping upward to

ward one another from said base ends at angles less than ninety degrees, said leg ends on adjacent ones of said clip members defining substantially V-shaped notches at said joining areas.

8. The clip member strand of claim 7 wherein said opposite leg ends on each of said clip members slope upwardly toward one another from said base ends at angles substantially 45°.

9. The strand of claim 8 wherein each of said leg members are reversely curved so that one of said leg members has a substantially S-shaped cross-sectional configuration and the other of said leg members has a substantially backward S-shaped cross-sectional con-

figuration, each leg member having an outwardly extending curved portion adjacent said base portion and merging into and inwardly curved portion, said leg members having terminal end portions extending outwardly from said inwardly curved portions and terminating at terminal ends facing outwardly of said base portion.

10. The strand of claim 9 wherein said leg ends on adjacent clip members define substantially V-shaped notches having notch sides extending upward from said base portions at substantially 45°.
